UNITED STATES PATENT OFFICE.

WILLIAM M. RYAN, OF CHICAGO, ILLINOIS, ASSIGNOR TO THE RYAN CAR COMPANY,
A CORPORATION OF MAINE.

SUBSILL AND DRAFT-ARM.

1,345,257.

Specification of Letters Patent. Patented June 29, 1920.

Application filed September 16, 1919. Serial No. 324,197.

To all whom it may concern:

Be it known that I, WILLIAM M. RYAN, a citizen of the United States, and resident of Chicago, county of Cook, and State of Illinois, have invented certain new and useful Improvements in Subsills and Draft-Arms, of which the following is a specification and which are illustrated in the accompanying drawings, forming a part thereof.

10 The invention relates to railway cars, and has for an object the provision of coacting sub-sills and draft arms, that may be applied to wooden cars which have become weakened through age or use or for any reason need strengthening in view of the increasingly heavy service being now required.

An illustrative embodiment of the invention is shown in the accompanying drawings in which—

20 Figure 1 is a plan view of the two ends of the device with center omitted for economy of space;

Figs. 2 and 3 are detail sections on lines 2—2 and 3—3 respectively of Fig. 4;

25 Fig. 4 is a detail plan view partly in section, of one end of the structure drawn to an enlarged scale, and

Fig. 5 is a detail section on line 5—5 of Fig. 4.

30 There are at present in use many old wooden cars which through age or long use or change in conditions of service, are now too weak to resist the loading customarily placed in cars of their capacity. To

35 strengthen such cars the structure provided by the present invention may be applied thereto and attached to the bolster, as 10, which is intended to illustrate a portion already forming a part of the car to be 40 strengthened, representing a well known type of bolster now in use. The structure may further be attached to the wooden sills of the old car, indicated at 11.

45 Some of the most severe stresses applied to railway cars are those due to draft and buff. To apply these stresses directly to the strengthening means of the present invention the structure comprises draft arms, as 12, 13, which may be secured to the wooden sills 11 by vertical bolts passed through the flanges, as 14, of the draft arms. The bolsters of the type illustrated have openings, as 15, therethrough, and this fact is taken advantage of by passing the draft arms 50 through these openings and causing them to

project beyond the bolster, as at 16. Under these circumstances the draft arms are preferably secured to the bolster, as by rivets 17.

For additional securing means between the draft arms and the bolster, as well as to 60 connect the draft arms to each other, upper and lower gusset plates, as 18 and 19, may be secured to both draft arms and bolster. Plate 18, is shown as overlying both draft arms and underlying the upper flange, as 20, 65 of the bolster and riveted to each, while plate 19 is shown as underlying both draft arms and as overlying the lower flange, as 21, of the bolster and being riveted to each.

The draft arms 13 and 14 are preferably 70 made of cast metal, in which case they may be made of any desired thickness and will not be limited to stock sizes of structural metal which might not be sufficiently strong in the size which could be obtained and 75 which would pass through the openings 15 in the bolster. The arms are shown as provided with draft lugs 22, buffing lugs, as 23, and with slots 24, 25, 26 to fit a known form of draft rigging. The arms may be 80 strengthened by flanges, as 27, 28, if desired.

For support of the wooden sills intermediate the bolsters, as well as to transmit draft and buffing stresses from bolster to 85 bolster, there are shown supplemental center sills, as 30, 31, shown as comprising stock shapes of channels. These channels may be and preferably will be secured to the wooden sills 11, as by vertical bolts (not 90 shown) passed through the flanges of the channels and the sills. They are shown as extending from bolster to bolster, and as lapping past the projections 16 of the draft arms. Under these conditions the 95 webs of the channels and draft arms are preferably secured together, as by rivets 32. The upper flanges of channels 30, 31, are thus shown as overlapping the upper flanges of the draft arms, and the gusset 100 plate 18, as overlying both; the rivets, as 33, will then pass through and secure together the three parts.

To preserve the spacing of the upper edges of the channels 30, 31, plates, as 34, 105 may be supplied, two being shown on the drawing. The connection of these channels with the wooden sills at their top edges will assist in keeping them in position, but at the bottom no such connection exists, and 110

moreover the stress caused by the car loading is a tensile stress at the bottom edges of the channels. To provide additional strength at this point a continuous plate in 5 the nature of a bottom cover plate, as 35, is shown as riveted to and closing the space between the channels 30, 31, from end to end thereof. Slots, as 36, are shown through which the brace rods, not shown, may be 10 extended.

The channels 30, 31, and the cover plate 35, thus practically form a box girder, and by virtue of the connection with the draft arms form a continuous strengthening 15 means between the draft gears at the two ends of the car.

To assist in transmitting buffing stresses from the draft arms to the bolster, the upper flange, as 14, of the draft arm may be 20 formed with an offset, as shown at 36', which will abut against the bolster. The edge of the upper flange of the bolster, at 37 (Fig. 5), is thicker than at 38 (Fig. 2), the difference being substantially equal to 25 the thickness of the gusset plate as preferably supplied. To allow the gusset plate 18 to lie flat on top of the upper flange of the channels 30, 31, and pass freely under the upper flange, as 38, of the bolster, a second 30 offset, as 39, is preferably formed in the upper flange 14 of the draft arms, said second offset being equal to the thickness of the upper flange of the channels. Throughout 35 the projection 16 of the draft arms the upper flanges are shown as formed at an angle to the web thereof, as at 40, to fit the angle of the inside of the flange 41 of the channel.

By means of the structure described both buff and draft stresses will be transmitted from end to end of the car, and from car to 40 car, through the reinforcing structure itself, and the buffing stresses which are the most severe will not depend entirely upon the rivets at any given joint between the parts.

I claim as my invention:

1. In car reinforcing means, in combination, draft arms extending through and projecting beyond the bolsters, sub-sills connecting with the inwardly projecting portions of the draft arms, gusset plates connecting said sub-sills and secured to the upper flanges of the bolsters, other gusset plates connecting the draft arms and secured to the lower flanges of the bolsters.

2. In car reinforcing means, in combination, a bolster, draft arms extending from the end of the car through and extending beyond said bolster and having a shoulder abutting against a flange of said bolster, sub-sills connected to the inwardly projecting ends of the draft arms, and gusset plates connecting the draft arms with each other, the sub-sills with each other and each to the bolster.

3. In car reinforcing means, in combination, a bolster, draft arms extending from the end of the car through and projecting beyond the bolster, a shoulder on the upper edge of each draft arm adapted to abut a flange of the bolster, sub-sills secured to the ends of the draft arms, and a second shoulder on each draft arm adapted to abut the end of a sub-sill.

WILLIAM M. RYAN.
